UNITED STATES PATENT OFFICE

JOHN B. HOLTZ, OF LOS ANGELES, CALIFORNIA, ASSIGNOR TO INVENTION DEVELOPMENT CORPORATION, OF CARSON CITY, NEVADA

DESIGN FOR AN ADVERTISING COLUMN

Application filed September 9, 1929. Serial No. 32,700. Term of patent 14 years.

To all whom it may concern:

Be it known that I, JOHN B. HOLTZ, a citizen of the United States, and a resident of Los Angeles, Los Angeles County, California, have invented a new, original, and ornamental Design for Advertising Column, of which the following is a specification, reference being had to the accompanying sheet of drawings, forming a part hereof.

In the drawings

Figure 1 is a front elevation of an adver-

tising column, showing my new design; and Figure 2 is a cross sectional view through said column.

The panels shown are provided to receive advertising displays.

I claim:

The ornamental design for an advertising column, substantially as shown and described.

JOHN B. HOLTZ.
